UNITED STATES PATENT OFFICE.

BENJAMIN E. GETCHELL, OF PLAINVILLE, CONNECTICUT, ASSIGNOR TO THE TRUM-BULL ELECTRIC MANUFACTURING COMPANY, OF PLAINVILLE, CONNECTICUT, A CORPORATION OF CONNECTICUT.

INCLOSED QUICK-MAKE AND QUICK-BREAK SWITCH.

Application filed January 13, 1923. Serial No. 612,460.

To all whom it may concern:

Be it known that I, BENJAMIN E. GETCHELL, a citizen of the United States of America, and residing at Plainville, in the county of Hartford and State of Connecticut, have invented new and useful Improvements in Inclosed Quick-Make and Quick-Break Switches, of which the following is a specification.

10 This invention relates to inclosed switches of the quick-make and quick-break type and particularly to those which include an interlocking engagement of the cover with the switch operating parts.

15 One object of this invention is to provide a simple and reliable quick-make and quick-break mechanism for an inclosed switch. Specifically I arrange the parts so that they can not be tampered with.

20 Another object of this invention is to provide a quick-make and quick-break means which will operate immediately, positively and independently of the position of the operating handle after the movement of the 25 contact has once started.

Another object is to provide a quick-make and quick-break means many parts of which can be made of sheet metal, some of which 30 interengage to form a quick-make and quick-break means, some of which function as spacing washers for aligning the parts so as to co-act with other parts of the construction and one or more of which is adapted to co-act with the box and cover interlocking 35 means.

Another object is to provide a spring operated quick-make and quick-break means of this type so constructed that the switch will be manually operable even should the spring 40 break while in use.

Another object is to provide a construction in which the operating spring is normally securely held in position but may be easily and quickly removed or replaced if 45 so desired.

Still another object is to provide an enclosed switch construction in which a wire or rod-like switch crank may be mounted and connected with a switch inside the box and may co-operatively engage with an external operating handle which handle may be of cast, sheet or wire-drawn metal as may be desired.

The parts are so constructed that they can

be readily made and assembled. In its preferred form, the invention contemplates the mounting of a more or less standard type of switch within a box and the provision of an operating handle suitably supported in one side of the box. Inside of the box is an operating crank having one end pivoted in a hub of the handle and the other end pivoted in the opposite side of the box. The operating handle has a lost motion connection with an intermediate member and the intermediate member has a further lost motion connection with the switch operating crank. A switch operating spring member is connected to the intermediate member of the handle hub inside the box.

Fig. 1 is a perspective view of a construction embodying the improvements of my invention, the cover of the box being shown open and the switch being shown in the closed circuit position.

Fig. 2 is a transverse sectional view showing the box closed with the switch in the open circuit position.

Fig. 3 is a transverse section through the hub of a modified handle.

Fig. 4 is a longitudinal sectional view showing the main parts of the quick-break mechanism inside the box, the parts being in the open circuit position, and the cover being omitted.

Fig. 5 is a similar fragmentary sectional view showing the switch in the closed circuit position.

Fig. 6 is a perspective view of the handle and hub parts and the end of the interior actuating crank.

The box may be of any suitable construction having, for instance, a body 7 and a hinged cover 8. Suitable means may be provided for interlocking the switch mechanism and the cover, as, for instance, the pivoted latch 9, having a hook 10, adapted to engage a pin 11 on the cover, when the cover is closed and the switch is in the closed circuit position. This pin 11 operates in a slot 12 and engages the shoulder 13 when the cover is closed so as to retract the latch 9 and disengage the locking finger 15 from the notch in the disc 16.

The switch mechanism proper may have any suitable type of stationary contacts 17 and movable switch blades 18 supported on an insulating base 21. When a plurality of

blades are employed, they may all be connected by an insulating cross bar 19.

The operating handle 22 may be of any suitable construction such as cast, sheet or wire drawn metal, but preferably is a casting. The actuating crank 23 may be of any suitable shape and may be formed, for instance, of a wire or rod bent to the desired shape. The crank 23 is operatively connected to the movable switch contacts 18 in any desired manner, as by one or more hooks 24 secured to the insulating cross bar 19.

The hub of the operating handle is made up of a series of sheet metal members suitably secured together. When the handle 22 is of sheet metal (Fig. 6) a washer 26 mounted in a hole in the side of the box forms a bearing for the hub, but when handle 22 is a casting washer 26 may be omitted and a corresponding boss may be cast integral with the handle, as shown in Fig. 3. In either case a notched locking washer 16 is mounted inside the box against the inner wall thereof.

25 The washer 27 may be sufficiently large to project beyond the edge of the locking washer 16 and assist in positioning the point 15 of the latch 9. One or more spacing washers 28 may be employed.

30 One or more of the washers 29 and 30 and also some of the other washers may have central openings for the end 31 of the actuating crank. All of these washers and handle 22 may be suitably secured together, for instance, by means of rivets. The opposite end 32 of the actuating crank is preferably pivoted in the opposite side of the box. A washer 33 surrounds washer 29 and these two have a lost motion lug and slot connection 34, so that they have a limited angle of independent rotation. This washer 33 is also provided with stop lugs 35 and 36, which project on opposite sides of the arm 37 of the actuating crank 23. This washer 33 also has a lug 38 hinged to a rod 39, whose opposite end is slidably engaged in a slotted guide 40, which has fingers to overstand the end of the spring 41.

50 When the parts are in the position shown in Figs. 2 and 4, the spring 41 on the rod 39 forces the washer 33, so that the lug 36 presses against the crank arm 37 and holds it against the stationary stop 42 with the switch in the open circuit position. A stop similar to 42 may be secured symmetrically therewith on the opposite wall of the box. In order to close the switch, it is necessary that the latch 9 be retracted from the notched washer 16, but this requirement is taken care of automatically by means of the pin 11 on the cover which engages the shoulder 13 on the latch and thus disengages the locking finger 15 from the notch in the disc 16 when the cover is closed as it should be before the switch is closed. As

the switch handle is swung in a clockwise direction as viewed from the right hand side of the switch, the hub of the handle rotates the disc 29, so as to take up the play of the lug and slot 34. Continued movement of the handle in the same direction causes the lug 35 on the washer 33 to press against the crank arm 37 and start the switch blades toward the closed circuit position. When the connection between the lug 38 and the rod 39 passes beyond the plane containing the axis of the crank 23 and the guide member of the rod 39, the spring 41 exerts its pressure to move the parts into the position shown in Figs. 1 and 5, which closes the circuit with a positive snap action. This circuit closing movement is limited by the abutment of the left hand arm of crank 23 against a stop 20 secured to inner left hand wall of the box (Fig. 2).

85 Reverse motion of the handle 22 causes the lug 36 to pick up the crank arm 37 and thus start the disengagement of the switch blades from the stationary contacts 17. Before they are disengaged, however, the point 90 of the connection between the thrust rod 39 and the lug 38 passes beyond the central plane of the throwing mechanism and suddenly exerts a powerful pressure to move the crank 23 to open circuit position.

95 It will thus be seen that both the opening and closing movements are placed beyond the control of the operator immediately after the movement of the contacts has started, so that the possibility of arcing is substantially minimized and complete movement in both opening and closing directions is assured.

100 The spring 41 is loosely mounted upon the pivoted thrust rod 39 with one end abutting against a head on the rod. To secure the spring in position, it is merely slipped upon the rod and forced back so that the rod may be slipped into the slotted guide member 40 and, when released, the spring and rod will 110 be securely retained in position by means of the bent-over ends of the slotted guide. To remove the spring it is merely necessary to reverse the attaching movement. The members 20 and 42 act as stops for the internal crank 23, and the switch is operative by means of the external handle even should the switch-throwing spring 41 be broken while in use but, in such a case, the switch will not act with its normal quick-make and 120 quick-break movement.

115 I claim:

125 1. In an electric switch, a casing, a switch in the casing, operating means for the switch, a switch throwing spring operably connected at one end with the operating means, a guide bar for said spring and an abutment for one end of said spring, said abutment having an open ended slot to detachably receive said guide bar and having 130

a projection adjacent said slot extending over the end of said spring to retain said spring in operative position.

2. An inclosed quick break switch construction, comprising a box, an operating handle having a hub mounted in one wall of said box, said hub comprising a series of sheet metal members, an annular member surrounding one of said members and having a lost motion connection therewith, an actuating crank supported in one of said members, said annular member having a lost motion connection with said crank and a quick make and quick break spring member connected to said annular member.

3. An inclosed switch including a box, fixed and movable switch contacts within the box, a crank within the box and having operable connection with the movable contacts, means for limiting the movement of said crank, a handle outside the box and having a lost-motion connection with said crank and spring pressed means responsive to the movement of the handle for operating the switch with a snap action, the said means including a spring and a support therefor extending through said spring and normally maintaining the handle in spring-pressed relation with said crank and the said crank being freely rotatable to move the switch into fully open or fully closed position when said spring is disabled.

4. An inclosed quick break switch comprising a box, a handle having a hub mounted in one wall of said box, a latch engaging part of said hub, an actuating crank pivoted in said hub, a member mounted concentrically with said hub and having a lost motion connection with part of said hub and a quick break spring member connected with said concentrically mounted member, said concentrically mounted member having a lost motion connection with said crank.

5. An inclosed quick break switch comprising a box, a handle having a hub mounted in one wall of said box, a member mounted concentrically with said hub and having a lost motion connection therewith and having projecting lugs, an actuating crank pivoted in said hub and having an arm extending between said lugs, a stationary stop for said crank and a quick break spring member connected to said concentrically mounted member.

6. An inclosed quick break switch com-

prising a box, a handle having a hub mounted to rotate in one wall of said box, said hub comprising a series of sheet metal members, a latch pivoted to the side of said box, and engaging one of said members, an annular member surrounding another of said members and having spaced lugs, an actuating crank pivoted in one or more of said members and having an arm adapted to swing between said lugs and a quick break spring connected to said annular member, one of said members overstanding the edge of said latch member.

7. An inclosed switch including a box, fixed and movable contacts within the box, a crank within the box having operable connection with the movable contacts, means limiting the movement of said crank, a handle outside the box and having a lost motion connection with the crank and spring means responsive to the movement of the handle for operating the switch with a snap action, the said spring means normally maintaining spring pressure between the said handle and said crank and said handle being rotatable to fully open and fully close the switch independently of said spring means said spring means including a coiled spring and a rod extending through and supporting said spring.

8. In an electric switch a pivotally supported member having a radial projection and two lateral projections, a crank pivotally supported in said member and having a portion extending between said lateral projections, a rod connected to said radial projection, a bifurcated hook shaped guide for said rod and a spring on said rod abutting against said guide for throwing said member with a snap action.

9. In an electric switch, a casing, a switch mounted in said casing, operating means for the switch having an external handle, a switch throwing spring operably connected at one end with the operating means, a guide bar for said spring, an abutment carried by said casing for one end of said spring, said abutment having an open ended slot to detachably receive said guide bar and having a projection adjacent said slot extending over the end of said spring to retain said spring in operative position and stops for said operating means independent of said guide bar and spring.

BENJAMIN E. GETCHELL.
